UNITED STATES PATENT OFFICE

CHARLES WILLIAM SOMERSGALE AND JOHN ANDREW BELILE, OF MONTEVIDEO,
URUGUAY

ELECTROMAGNETIC SELECTOR DEVICE

Application filed May 7, 1928, Serial No. 275,806, and in Great Britain December 7, 1927.

This invention comprises a radial selector which consists of a number of electro-magnets corresponding to the number of functions to be operated arranged in such a manner that their poles are equidistant from a common armature which is suspended or so held as to enable it to have the freedom of movement necessary to assure the required operation on its being attracted by any one electro-magnet.

On any one magnet being energized, the armature is attracted and retained so long as the energizing current is applied and if during this period any other magnet or magnets in the system be energized, the attraction or resultant attraction thereof is insufficient to dislocate the armature since the attractive force to which the armature is subjected by the magnet to which it has been drawn is greater than the force or resultant of the total forces to which it is subjected by the energization of any one or more of the other magnets in the system. This is due to the fact that the armature is at a greater distance from the poles of the other magnets than it is from the one by which it was attracted in the first instance and further to the fundamental law that the attractive force varies inversely as the square of the distance.

The attraction of the ball or equivalent by any one magnet is made use of to operate a contact or bank of contacts for the making and breaking of local or other circuits the device being then purely and simply a selective relay with certain inherent peculiarities.

It is possible to employ the device to perform some function other than the operation of contacts, thus the basic principle may be expressed as follows:

Any number of electro-magnets are placed in such relation to a common armature as to enable any one of the said magnets to attract the said armature and to retain it so long as the energizing current be applied, with a magnetic attraction greater than that to which it is subjected by the subsequent concomitant energization of any other magnet in the system or resultant attraction of any combination thereof, thus providing an electrically

operated selective device for the making and breaking of circuits or for other functions.

An embodiment of the invention is illustrated in the accompanying drawings in which:

Fig. 1 is a side elevation.

Fig. 2 a plan view.

Fig. 3 a vertical section.

Fig. 4 a section on line 4—4 of Fig. 3.

The device is shown as adapted to operate a plurality of pairs of contacts *a*, *b*, eight pairs being shown in the drawings, there being provided for each pair of contacts an electro-magnet *c*, mounted between two frame members *d*, *e* the cores *c*¹ of said magnets being secured to the base member *d* and projecting upwardly through the member *e* to a capping plate *f*. The member *e* is provided with a concave or dished surface *e*¹ in which an armature, in the form of a ball *g*, normally rests, the concave surface being such that said armature will have freedom of movement in the direction of the energized magnet and the magnets being so arranged that their poles are equidistant from said armature in its normal position.

A ring *h* is interposed between the frame member *e* and the capping plate *f* and is provided with inwardly directed shoulders or abutments *h*¹, the shoulders being equally spaced between the cores of the magnets in such a manner that when the armature is attracted by any one of the said magnets, it abuts against the adjacent shoulders, the armature being thus prevented from contacting with any other magnet, as shown in Figs. 2 and 4.

The contacts *a*, *b* are conveniently mounted on the base member *d* as by means of screws *d*¹, the inner one of each of said pairs of contacts being provided at its upper end with an inwardly directed pin or the like *b*¹ passing through a hole *c*² in the core *c*¹ of each magnet and upon energization of one of the magnets, the respective pin is engaged by the armature *g* to close the circuit between contacts *a* and *b*.

The ball or equivalent should be of soft iron of high permeability and should be copper plated to avoid rust and prevent physi-

cal contact of iron to iron which is undesirable in all electro-magnetic devices where a small amount of residual magnetism can be a disadvantage.

5 One of the uses for which this device is suitable is in an intercommunication telephone system wherein each instrument is fitted with one of these selectors having as many magnets as there are instruments in 16 the system less one.

On ringing up any subscriber in the system by means of a mechanical stick button the battery current is applied to one coil of the caller's, and one coil of the called, instrument. It is only necessary for the receiver to be removed from the latter instrument to establish communication. Owing to the principles mentioned any other stations calling those which are thus in communication are unable to interfere or establish communication therewith since although they are able to energize the coils of the relays in the instrument called, they are unable to attract the armature and their lines remain 25 dead until the previous communication is terminated and the electro-magnets de-energized by the replacement of the receivers.

With this device the system can of course be elaborated to provide all the additional 30 indications of special combinations sometimes furnished in apparatus of this type for special reasons.

What we claim as our invention and desire to secure by Letters Patent of the United 35 States is:—

1. An electro-magnetic selector device comprising in combination a plurality of independently energizable electro-magnets, not less than three, disposed in a circle about 40 a common centre, an armature, and means for normally holding said armature at said common centre, the said armature having freedom of movement radially towards any of said electro-magnets.

45 2. An electro-magnetic selector device comprising in combination, a number of electro-magnets corresponding to the number of functions to be operated, a common armature in the form of a ball, means whereby the 50 said armature is normally held equidistant from said magnets when the latter are not energized said armature having freedom of movement in the direction of an energized electro-magnet.

55 3. An electro-magnetic selector device comprising in combination, a number of electro-magnets corresponding to the number of functions to be operated, a common armature in the form of a ball, a concave surface upon 60 which said armature is normally held equidistant from said magnets when the latter are not energized and allowed freedom of movement necessary to assure the required 65 operation in the direction of an energized electro-magnet.

4. An electro-magnetic selector device comprising in combination a number of electro-magnets corresponding to the number of functions to be operated, a common armature, means whereby the said armature is normally held equidistant from said magnets when the latter are not energized said armature having freedom of movement in the direction of any energized electro-magnet, and abutments interposed between the cores of 70 said magnets to ensure contact of the armature with only one of the cores.

5. An electro-magnetic selector device comprising in combination, a number of pairs of contacts, a number of electro-magnets corresponding thereto, an inwardly extending pin on the inner of each pair of contacts, the core of each magnet having a hole for the passage of said pin and a common armature which upon attraction by the core of any of 80 the magnets operates the contacts corresponding to said magnet.

6. An electro-magnetic selector device comprising in combination a number of pairs of contacts, a number of electro-magnets corresponding thereto, a common armature in the form of a ball, means whereby the said armature is normally held equidistant from 85 said magnets when the latter are not energized, an inwardly extending pin on the inner of each pair of contacts, the core of each magnet having a hole for the passage of said pin and said armature upon attraction by the core of an energized magnet engaging the pin to close the circuit between 90 the pair of contacts corresponding to said magnet.

7. An electro-magnetic selector device comprising in combination a number of pairs of contacts, a number of electro-magnets 105 corresponding thereto, a common armature in the form of a ball, a member having a concave surface upon which said armature is normally held equidistant from said magnets when the latter are not energized and allowed freedom of movement in the direction of an energized magnet, an inwardly extending pin on the inner of each pair of contacts, the core of each magnet having a 110 hole for the passage of said pin, said armature upon attraction by the core of an energized magnet engaging the pin to close the circuit between the pairs of contacts corresponding to said magnet.

8. An electro-magnetic selector device comprising in combination a number of pairs of contacts, a number of electro-magnets corresponding thereto, a common armature in the form of a ball, a member having a concave surface upon which said armature is normally held equidistant from said magnets when the latter are not energized and allowed freedom of movement in the direction of an energized magnet, abutments interposed between the cores of 115 said magnets, 120
